United States Patent Office.

FREDERICK A. SEBORN, DAVID R. DUNLAP, AND JOACHIM F. C. GEIST,
OF ZANESVILLE, OHIO.

Letters Patent No. 82,442, dated September 22, 1868.

IMPROVED WINDOW-SHADE FIXTURE.

The Schedule referred to in these Letters Patent and making part of the same.

TO ALL WHOM IT MAY CONCERN:

Be it known that we, FREDERICK A. SEBORN, DAVID R. DUNLAP, and JOACHIM F. C. GEIST, of Zanesville, in the county of Muskingum, in the State of Ohio, have invented a new and improved Fixture and Combination for Raising and Lowering Window-Curtains; and we do hereby declare that the following is a full and exact description thereof, reference being had to the accompanying drawings, and the letters of reference marked thereon.

The nature of our invention consists in so arranging the curtain, roller, and pulleys with the cords, that the curtain may be rolled either from the bottom to the top, or from the top to the bottom, or in both directions at the same time, so that the upper sash may be lowered, and the current of air pass unobstructed over the curtain and roller, or the lower one may be elevated, and the current pass unobstructed into the room, or both may be done at the same time.

The advantage of this invention, to secure perfect ventilation from the top, and at the same time close the lower part of the window, must be obvious to all, and this perfect ventilation from the top can be secured without the disagreeable consequence, resulting from stationary rollers, of having the curtain either fixed to the sash, or, if not so fixed, permitting the current of air passing through the opening caused by lowering the upper sash blowing the curtain into the room.

To enable others skilled in the art to make and use our invention, we proceed to describe its construction and operation.

The accompanying drawings represent an ordinary window, so constructed that the upper sash may be lowered by weights or springs, and the lower one elevated in the same manner; and they show that the upper sash is lowered, and also show the curtain and roller marked in the drawings A. The pulleys are one at each upper corner of the window, and are marked B B. The cords are marked respectively C C, E E, and F, and the small hooks attached to the ends of the roller marked D D.

One of the cords C is attached to the hook D, at one end of the roller, and the other at the other end. They are then passed over the pulleys B B, and come together and are fastened to the small button marked G, on the side or casing of the window. By lifting the cords C C from their fastening on the button G, the roller A will fall or be lowered, and by pulling the cords down, the roller will be raised. The cords E E pass once around the roller at or near each end, in a little groove for the purpose, and are fastened at the top and bottom of the window. As the roller falls or is lowered, the cords E E, by being thus passed around the roller, as already stated, cause the roller to revolve, and thus roll the curtain from the top downwards. When the curtain is elevated to the desired height, and the cords C C fastened to keep it in its place, by pulling the cord F, the roller revolves, and the curtain is raised from the bottom, the hooks D D being so fastened to the ends of the roller as to permit it to revolve.

Instead of having the pulleys B B fastened to the upper corners of the window-frame or casing, they may be placed in a moulding or bar which may be fastened across the window, either for the purpose of being more ornamental or more convenient, as may be desired.

The cords E E, not only in passing around the roller, act in rolling the curtain, but also serve to keep the same in its place.

We are aware that a cord similar to the cord C has been employed by Tanner and Gorton and others, to raise and lower both ends of the upper roll at once; and we are also aware of G. M. White's patent, dated August 7, 1866, in which a fixed rope, running around one end of each roll, is employed for the purpose of rotating the rolls as they are raised and lowered. We are also aware that a cord, F, operating to roll up the curtain, has been used ever since curtains were made. We do not claim these different parts by themselves, but simply the combining of them all together in a single device, whereby they are made to operate each in connection with the other, and the advantages of all are utilized to the fullest extent.

What we claim as new, and desire to secure by Letters Patent, is—
The arrangement of the cord C, pulleys B B, roll A, fixed cord E, and cord F, substantially as shown and described.
